UNITED STATES PATENT OFFICE

OSCAR S. DORR, OF FOND DU LAC, WISCONSIN, ASSIGNOR TO GOODBAR MANUFACTURING CORPORATION, OF NEW YORK, N. Y., A CORPORATION OF NEW YORK

GARMENT

Application filed March 2, 1931. Serial No. 519,288.

This invention relates to improvements in garments and more particularly to garments having shoulder straps, an object of the invention being to prevent such shoulder straps from falling from the shoulders of the wearer during use, and further, the application of such means to garments of various kinds as commonly constructed and without change in the appearance of the garment or in the general form or construction.

With these and other ends in view, the invention consists in the applying of a stiffening member to each shoulder strap of a garment by enclosing the same therein in a manner to hold the strap in an upright position relative to the upper portion of the garment and prevent the strap from swinging laterally and crinkling which would cause it to slip from the shoulder of the wearer. The invention further consists in detachably attaching such stiffening member to a shoulder strap so that said member may be quickly and easily removed when the garment is to be washed, and in providing certain other new and useful features, all as hereinafter set forth and more particularly pointed out in the appended claims, reference being had to the accompanying drawings, in which—

Figure 1 is a perspective view showing the application of the invention in use;

Fig. 2 is a perspective view of a garment having shoulder straps to which the invention is applied; and Fig. 3 is a central longitudinal section through an end portion of a shoulder strap.

As shown, 1 indicates the upper portion of an undergarment which is provided with shoulder straps 2 of any desired design or configuration to pass over the shoulders of the wearer and support the garment. The ends of each strap 2 are permanently sewed in the usual manner to the front and back of the garment, upon the inner surface thereof adjacent the upper edge portion 3 of such garment, and each strap at its rear end or end at the back of the garment, is formed tubular or hollow to provide a pocket 4 into which is slipped endwise through a pocket mouth or opening 5 at the under side of the strap, a stiffener strip 6 of any suitable flex-

ible resilient material such as a thin strip of steel, whalebone, or the like. The pocket 4 extends below the upper edge 3 of the garment 1 as at 7 and the sides and end of this portion of the pocket are very securely sewed or otherwise secured to the inner side of the garment so that the lower end of the stiffener 6 will extend into this portion of the pocket and be thus held against swinging edgewise without crumpling the garment body. Therefore when the garment is in place upon the wearer with the upper edge portion 3 secured about the wearer's body beneath her arms, the straps will be held substantially at right angles to the upper edge of the garment body by the stiffeners which extend downward into the portions 7 of the pockets which are firmly secured to the garment, the upper end portions of these stiffeners extending upward in the straps to nearly the top of the wearer's shoulders, and as these stiffeners are held substantially at right angles to the garment edge by their extension into the secured lower ends of the pockets, the straps are held thereby against swinging laterally and slipping from the shoulders of the wearer. The stiffeners are preferably very thin and flexible so that they will bend readily in the direction of their thickness and thus conform readily to the back and shoulders of the wearer, yet have rigidity in the direction of their width to hold the straps in an upright position relative to the upper portion of the garment, without being noticeable. By providing pockets in the straps to receive the stiffeners these stiffeners may be quickly and easily removed when it is desired to wash the garment, by simply slipping them endwise through the open mouths of the pockets.

The size or form of the shoulder straps or the construction of the garment, are immaterial, as the pockets in the straps may be made to fit the stiffeners regardless of the width, shape or length of the straps, and such other changes as fall within the terms of the appended claims are contemplated.

Having thus fully described my invention, what I claim is:—

1. A garment having a shoulder strap formed with a longitudinal pocket having a

mouth and with said pocket extending in a substantially vertical direction downwardly of the body of the garment to a point well below the upper edge portion of said body 5 and secured thereto at substantially right angles to said edge, and a thin flexible stiffening strip in said pocket removable endwise through said mouth and extending to the lower end thereof and held in an upright 10 position by its engagement within said lower end portion of said pocket which is secured to said garment vertically downward from the upper edge of said garment, and extending upwardly in said pocket to adjacent the 15 mid-point of said strap.

2. A garment having shoulder straps each formed of two thicknesses of material to form a pocket with one end portion of each strap extended vertically downward and 20 firmly secured to the inner face of said garment body at substantially right angles to the upper edge thereof and each strap formed at its inner side intermediate its ends with a pocket mouth; and a stiffening strip 25 insertable endwise in each pocket through said mouth with its lower end extending to the lower end of said pocket well below the upper edge of said garment, to hold said strap in a position substantially at right angles to 30 the upper edge of said garment.

In testimony whereof I affix my signature.
OSCAR S. DORR.
